UNITED STATES PATENT OFFICE.

SAMUEL M. LEWIS, OF PORTSMOUTH, VIRGINIA.

JOURNAL-BOX.

SPECIFICATION forming part of Letters Patent No. 767,581, dated August 16, 1904.

Application filed August 18, 1900. Serial No. 27,294. (No model.)

To all whom it may concern:

Be it known that I, SAMUEL M. LEWIS, a citizen of the United States, and a resident of Portsmouth, in the county of Norfolk and 5 State of Virginia, have invented a new and useful Improvement in Journal-Boxes, of which the following is a specification.

This invention relates more particularly to that class of axle-boxes in which the lid is 10 hinged to a pintle-lug arranged at the top of the box and provided with a flat spring which is secured at its lower end to the lid and adapted to bear at its upper free end against said lug. Heretofore the lid-spring has been 15 constructed to yieldingly interlock with a shoulder, notch, or flat face of the pintle-lug for holding the lid in its open position; but this construction requires the lid to be opened to a predetermined position in order to cause 20 the spring to interlock with the pintle-lug.

One of the objects of my invention is to provide a simple and effective retaining device which will hold the lid in a more or less open position without requiring the same to 25 be opened to a definite or predetermined extent.

Another object of my invention is to improve the construction of the axle-box with a view of effectually preventing the entrance of 30 dust at the edges of the lid.

In the accompanying drawings, Figure 1 is a vertical longitudinal section of an axle-box containing my improvements, showing the lid closed. Fig. 2 is a similar section showing the lid open. Fig. 3 is a front view of 35 the box with the lid closed. Fig. 4 is a similar view with the lid open.

Like letters of reference refer to like parts in the several figures.

40 A is the lubricant-chamber of the axle-box, and A' the usual filling-opening in its front wall.

B is the lid, which is hinged to the box by the transverse pintle b, which passes through 45 the usual eyes c of the lid and the upright pintle-lug d, arranged at the top of the axle-box.

The filling-opening A' is provided with the usual outwardly-projecting marginal rim a, 50 and this rim is formed around the four sides

of the filling-opening with a rabbet or recess a', in which the lid is seated or countersunk when closed, as shown in Fig. 3. The lid is provided at its lower edge with a central lip or thumb-piece a'' for opening it, which lip is seated in a notch a''', formed in the rim a, when the lid is closed. By countersinking the lid in this manner the rim a incloses the edges of the lid and forms a guard which prevents dust and cinders from entering the axle- 60 box at this point.

E is the lid-spring, arranged on the inner side of the lid and secured at its lower end to the same. The pintle-lug d is provided in its under side with an opening or recess f, in which 65 the upper end of the lid-spring engages when the lid is closed, as shown in Fig. 1. This recess has a straight upright front wall, and the upper portion of the lid-spring is bent so as to bear squarely against said wall, as shown at f' in 70 Fig. 1. The free end of the spring is curved or rounded, as shown at f'', and is adapted to bear against the front face of the pintle-lug when the lid is opened for holding the lid in its open position. The upper front portion g of said 75 face is preferably concentric with the pintle b, as shown, while the remaining front portion thereof is constructed of gradually-increasing radius to form a cam or eccentric g', which terminates at the front wall of the recess f. 80

Upon opening the lid the free end of its spring E rides over the lower front edge of the recess f and up on the eccentric face g' of the pintle-lug d. In riding over the lower front edge of said recess the lid-spring is further 85 strained or deflected, and in passing upwardly over the eccentric face g' of the pintle-lug the same is somewhat relaxed, the free end of the spring bearing against the upper concentric face g of said lug when the lid is raised to the 90 position shown in Fig. 2, in which position the box can be conveniently packed. The resistance due to the frictional contact of the strained lid-spring with the face of the pintle-lug is greater than the weight of the overhanging lid when open, and the spring therefore holds the lid in its open position, and as the eccentric face g' of the lug widens or increases in radius downwardly, the spring is further strained and its resistance correspond- 95 100

ingly increased as its free end approaches the lower end of the eccentric face. By this construction the spring reliably holds the lid in any position in which it may be left or placed 5 in opening it and no care is required to open the lid fully or to a predetermined extent, as is necessary when its spring interlocks with a shoulder, flat face, or notch of the pintle-lug. As the concentric and eccentric faces g g' of 10 the lug are practically smooth and continuous, the lid-spring slides freely over the same and the lid can be opened or closed with comparatively little effort. Upon closing the lid its flat end portion enters the recess f in the 15 under side of the pintle-lug, holding the lid in its closed position.

I claim as my invention—

The combination of a journal-box provided with a filling-opening and having at its top a

substantially upright pintle-lug, the front 20 face of which is convexed continuously from the top to the bottom of the lug and the lower portion of said front face being eccentric to the pintle and increasing in radius toward the lower end of the lug, said lug having at its 25 lower end a recess, a lid hinged to said pintle-lug, and a spring secured on the inside of the lid with its free end adapted to bear on the outer face of said pintle-lug and enter said recess, and in the latter position hold the lid 30 closed, substantially as set forth.

Witness my hand this 13th day of August, 1900.

S. M. LEWIS.
